(57) **CLAIM**

The ornamental design for the cable cage, as shown and described.

DESCRIPTION

FIG. 1 is a top view showing a first embodiment of a cable cage showing my new design;

FIG. 2 is a left side view thereof;

FIG. 3 is a right side view thereof;

FIG. 4 is a front view thereof;

FIG. 5 is a rear view thereof;

FIG. 6 is a bottom view thereof;

FIG. 7 is a front perspective view thereof;

FIG. 8 is another front perspective view thereof;

FIG. 9 is a top view thereof;

FIG. 10 is a left side view thereof;

FIG. 11 is a right side view thereof;

FIG. 12 is a front view thereof;

FIG. 13 is a rear view thereof;

FIG. 14 is a bottom view thereof;

FIG. 15 is a front perspective view thereof; and,

FIG. 16 is another front perspective view thereof.

The broken lines shown in FIGS. 8 and 16 are for the purposes of illustrating environmental structure and form no part of the claimed design.
